CLAIM

The ornamental design for a camera with remote, as shown and described.

DESCRIPTION

FIG. 1 is a front perspective view of a camera with remote, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its usage state diagram thereof;

FIG. 10 is an enlarged detail view of area 10 in FIG. 1 thereof;

FIG. 11 is an enlarged detail view of area 11 in FIG. 1 thereof;

FIG. 12 is an enlarged detail view of area 12 in FIG. 1 thereof;

FIG. 13 is an enlarged detail view of area 13 in FIG. 1 thereof;

FIG. 14 is an enlarged detail view of area 14 in FIG. 1 thereof;

FIG. 15 is an enlarged detail view of area 15 in FIG. 1 thereof;

FIG. 16 is an enlarged detail view of area 16 in FIG. 2 thereof;

FIG. 17 is an enlarged detail view of area 17 in FIG. 2 thereof;

FIG. 18 is an enlarged detail view of area 18 in FIG. 2 thereof;

FIG. 19 is an enlarged detail view of area 19 in FIG. 2 thereof;

FIG. 20 is an enlarged detail view of area 20 in FIG. 2 thereof; and,

FIG. 21 is an enlarged detail view of area 21 in FIG. 3. The dash-dash broken lines in the drawings illustrate the portions of the camera with remote, which form no part of the claimed design.

The dot-dash lines represent a boundary for the purposes of disclosing areas of enlargement and form no part of the claimed design.
